UNITED STATES PATENT OFFICE.

JOHANN HOFFMANN, OF VIENNA, AUSTRIA.

DEVICE FOR PACKING OR STUFFING TUBES FILLED WITH SAND OR THE LIKE BY MEANS OF KNOCKING OR BEATING.

Application filed January 7, 1924. Serial No. 684,913.

To all whom it may concern:

Be it known that I, JOHANN HOFFMANN, manufacturer, residing at Vienna, in the Republic of Austria, have invented certain new and useful Improvements in a Device for Packing or Stuffing Tubes Filled with Sand or the like by Means of Knocking or Beating, of which the following is a specification.

This invention relates to a device for packing or stuffing tubes filled with sand or the like by means of knocking or beating.

Devices for knocking or beating tubes filled with sand are already known, in which the tube is caused to rotate about its axis and the hammers play upon the outside of the tube and thereby carry out a longitudinal movement with respect to the tube.

The present invention consists in that beside the longitudinal movement the hammers carry out a simultaneous movement around the immovable tube. Further the invention has for its object to provide a knocking or beating device of such construction, that the knocking or beating force of the rotating hammers can be regulated by varying the tension of the knocking springs by means of adjustable tensioning cams.

One mode of carrying out the present invention is shown by way of example on the accompanying sheets of drawings, in which Fig. 1 is a front view, and Fig. 2 a side view of the machine according to the present invention. Fig. 3 illustrates the knocking device in vertical section, and Fig. 4 the same in horizontal section. Figs. 5 and 6 illustrate the knocking device in front- and plan view respectively. Fig. 7 is a plan view of the non-rotating part of the knocking device, and Fig. 8 a front view of this part, whereby the left hand side is shown in section. Figs. 9 and 10 illustrate the guide-discs of the tensioning cams in plan view and section respectively. Figs. 11 and 12 show the adjusting disc of the tensioning cams in plan view and section respectively. Figs. 13, 14 and 15 illustrate a tensioning cam in side view, front view and plan view respectively. Fig. 16 shows a hammer, and Fig. 17 a tensioning lever for the movement of the hammers.

The machine frame consists of three pillars 1, 2 and 3, provided with transverse connecting members 4 at the top and bottom. 55 A bottom bearing 5 furnished with adjust-

ing screws 6 and a top guide 7 serve for clamping or fixing the tube T to be knocked or hammered. The knocking or beating arrangement comprises a bottom member 8, which is guided on the pillars 1, 2 and 3 by means of arms 9 and rollers 10 and is adapted to carry out an up- and down movement only along the tube, and a hammer-support 11 which is adapted to perform a rotating movement around the tube. The bottom member 8 is suspended from ropes 12 or the like, which pass over pulleys 13 to winding drums 15, arranged on a shaft 14. The winding drums are operated by a toothed wheel 16 secured to the end of the shaft 14 and meshing with a pinion 17 keyed to a shaft 18, which is provided with and rotated by a driving pulley 19. A driving pulley 21 is arranged on a shaft 20 and an endless belt 22 passes from the pulley 21 over a driving pulley 23 of the knocking arrangement and over a guide pulley 24 and a tension pulley 25 back to the driving pulley 21. The shaft 26 of the driving pulley 23 carries a bevel wheel 27, which meshes with a rim of gear wheel 28 of the hammer-support 11 and thus is adapted to rotate the latter.

The hammer-support consists of a tubular member 29 (Figs. 3 and 4) and a disc 30, which is provided with the rim of gear wheel 28. The disc carries radially disposed hammer-casings 31, closed at the outer side by lids 32 and at the top by a cover-plate 33. A hammer-sleeve 34 is movably arranged in every hammer-casing and a hammer 35 is screwed into the former, the hammer-head 36 is adapted to pass through an opening 37 in the member 29. A knocking spring 38 is disposed between the hammer 35 and the hammer-sleeve 34, one end of the said spring resting against the lid 32 of the casing and the other end thereof against the hammer-sleeve 34, which is secured against rotation by a bolt 39 passing through a slot 40 of the disc 30. The end of the bolt 39 is gripped by the free end 41 of a tension-lever 42, which is rotatably mounted on a pin 43 fixed to the disc 30.

The lower or bottom part of the knocking arrangement is formed by an annular member or ring 44 with a stepped bottom 45, between its arms 9 is arranged the bearing of the shaft 26. A guide disc 46 is secured to the top step of the bottom 45 and is provid-

ed with slots 47, in which radially adjustable tensioning cams 48 are disposed. By means of a slide-block 49 every tensioning cam is disposed in its respective slot 47 in 5 the guide disc 46 and passes by means of a bolt 50 through a curved slot 51 of a regulating disc 52, which is rotatably disposed below the guide disc 46, the rotation being effected by means of a handle 53 in the ring 10 44 and limited by the slot 54. Each tensioning cam 48 is provided with a screw-threaded end 56, which is passed through a slot 55 in the bottom 45 and is secured against leaving its position toward the top 15 by a nut 57.

The tensioning cams 48 are provided with a curved guiding surface 58. The end 41 of the tension-lever 42 is enlarged and furnished with a slot 59, which surrounds the 20 bolt 39. The hammer is provided with screw-threads 60 and with a square recess 61 for the insertion of a key, in case it is desired to move the hammer into or out of its guide-sleeve 34 by means of screwing in 25 or out the hammer.

The machine operates in the following manner:

The tube T, which is filled with sand and is to be knocked or beaten, is vertically and 30 centrally disposed between the bottom bearing and the top guide. On setting the machine into operation the entire knocking arrangement carries out an altering up- and down movement along the tube, whereby 35 the upper part of the same performs a rotary motion around the tube. When the disc 30 is rotating the ends 41 of the tension-lever come into contact with the guide-surfaces 58 of the tensioning cams 48 and 40 thereby are forced to move outwardly by turning about their pivots 43. In consequence thereof the guide-sleeve 34 together with its hammer is shifted outwardly thereby tensioning the knocking spring 38. As 45 soon as the end 41 of the tension-lever leaves a tension-cam 48, the hammer 35 together with the hammer-sleeve 34 are tossed forward by the action of the relieved knocking spring 38, the hammer-head 36 passing 50 through the opening 37 and is brought to play on the tube T to be knocked or beaten. This procedure is repeated in the same manner when a tension-lever 42 passes one of the tensioning cams 48. The tension of all 55 knocking springs 38 depends on the larger or smaller distance of the tensioning cams from the centre of the knocking arrangement. If the said cams are disposed in a greater distance from the centre of the said 60 arrangement the knocking springs will be more tensioned and therefore the hammer will play with greater force on the tube. If the cams are adjusted nearer toward the 65 centre, the springs will not be compressed to such an extent as when the cams are

farther away from the centre. In order to simultaneously and uniformly vary the tension of all knocking springs on which the knocking force executed by the hammer-head depends, it is sufficient to vary simultaneously and to the same extent the position of the tensioning cams 48, this being accomplished by rotating the regulating disc 52 by means of its handle 53. In Fig. 4 of the drawings the tensioning springs 48 70 are disposed in their outermost position and effect the greatest tensioning of the knocking springs. When rotating the regulating disc clockwise the curved slots 51 cause the simultaneous and uniform inward movement of all tensioning cams, whereby all knocking springs are less tensioned when the tension levers are passing, and the hammers act with a smaller force. As during the revolution of the hammers the regulating disc solely participates on the movement along the tube, the regulation of the knock of the hammers is rendered possible without having to stop the machine. 80

I claim—

1. A device for rapping tubes which have been filled with sand, comprising a member arranged to execute a movement longitudinally of the work only and carrying clamping jaws, and a superposed member carrying hammers, and arranged to rotate about the work, said last named member being arranged to participate in the longitudinal movement of the first named member. 90

2. A device for rapping tubes which have been filled with sand, comprising a member arranged to execute a movement longitudinally of the work only and carrying clamping jaws, and a superposed member carrying hammers, and arranged to rotate about the work, said last named member being arranged to participate in the longitudinal movement of the first named member, springs to impart rapping force to the hammers, and means to vary the tension of the springs, said means including adjustable devices. 100

3. A device for rapping tubes which have been filled with sand, comprising rapping hammers arranged for longitudinal movement and also for revolute movement about the work, springs arranged to impart rapping force to the hammers, means to vary the tension of the springs and including adjustable devices, and a common regulating element for said adjustable devices. 115

4. A device as set forth in claim 3 including tensioning levers for the hammers operable by the said tensioning devices and arranged to effect movement of the hammers 120 and tensioning of the springs in accordance with the adjustment of the said tensioning devices. 125

5. A device for packing tubes filled with sand or the like, comprising in combination, 130

- means for immovably securing the filled tube in position, and a beating device adapted to play on the outside of the tube, the said beating device consisting of two parts, 5 one part carrying tensioning cams and being adapted to carry out a movement in the longitudinal direction of the tube and the other part thereof being disposed above the part first mentioned and supports a hammer and 10 further is adapted to carry out a rotary movement around the tube whereby the hammer is withdrawn from the tube by the said cams and after the latter have left the hammer, the same is forced to play on the 15 tube, and during the longitudinal movement of the first part the rotary second part also is taken along by the latter, so as to perform also a simultaneous longitudinal movement.
- 20 6. A device for packing tubes filled with sand or the like, comprising in combination, means for immovably securing the filled tube in position, and a beating device adapted to play on the outside of the tube, the 25 said beating device consisting of two parts, one part carrying tensioning cams and being adapted to carry out a movement in the longitudinal direction of the tube and the other part thereof being disposed above the 30 part first mentioned and supports a number of radially disposed hammers and further is adapted to carry out a rotary movement around the tube whereby the hammers are withdrawn from the tube by the 35 said cams and after the latter have left the hammers, the same are forced to play on the tube, and during the longitudinal movement of the first part the rotary second part also is taken along by the former, so as to 40 perform also a simultaneous longitudinal movement.
7. A device for packing tubes filled with sand or the like, comprising in combination, 45 means for immovably securing the filled tube in position, and a beating device adapted to play on the outside of the tube, the said beating device consisting of two parts, one part carrying tensioning cams and being adapted to carry out a movement in a longitudinal 50 direction of the tube and the other part thereof being disposed above the part first mentioned and supports a flexible hammer and further is adapted to carry out a rotary movement around the tube whereby the flexible hammer is withdrawn from the tube and placed in tension by the cams, and 55 during the longitudinal movement of the first part the rotary second part also is taken along by the latter, so as to perform also a simultaneous longitudinal movement.
- 60 8. A device for packing tubes filled with sand or the like, comprising in combination, means for immovably securing the filled tube in position, and a beating device adapted to play on the outside of the tube, 65
- the said beating device consisting of two parts, one part carrying tensioning cams and being adapted to carry out a movement in the longitudinal direction of the tube and the other part thereof being disposed above the part first mentioned and supports a number of radially disposed flexible hammers and further is adapted to carry out a rotary movement around the tube, whereby the flexible hammers are withdrawn from the tube and placed in tension by the cams, and during the longitudinal movement of the first part the second part also is taken along by the latter, so as to perform also a simultaneous longitudinal movement. 70
9. A device for packing tubes filled with sand or the like, comprising in combination, means for immovably securing the filled tube in position, and a beating device adapted to play on the outside of the tube, the 75 said beating device consisting of two parts, one part carrying adjustable tensioning cams and being adapted to carry out a movement in the longitudinal direction of the tube and the other part thereof being disposed above the first mentioned part and supports a flexible hammer and further is adapted to carry out a rotary movement around the tube, whereby the flexible hammer is withdrawn from the tube and its beating force may be varied by the said adjustable cams, and during the longitudinal movement of the first part the rotary second part also is taken along by the latter, so as to perform also a simultaneous longitudinal movement. 80
10. A device for packing tubes filled with sand or the like, comprising in combination, means for immovably securing the filled tube in position; and a beating device adapted to play on the tube, the said beating device consisting of two parts, one part carrying adjustable cams and being adapted to carry out a movement in the longitudinal direction of the tube and the other part thereof being disposed above the first mentioned part of radially disposed flexible hammers and further being adapted to carry out a rotary movement around the tube whereby the flexible hammers are withdrawn from the tube and their beating force may be varied by the said adjustable cams, and during the longitudinal movement of the first part the rotary second part also is taken along by the latter, so as to perform also a simultaneous longitudinal movement. 90
11. A device for packing tubes filled with sand or the like, comprising in combination, means for immovably securing the filled tube in position, and a beating device adapted to play on the outside of the tube, the said beating device consisting of two parts, one part carrying adjustable tensioning cams and being adapted to carry out a movement in the longitudinal direction of the tube 110
- 120
- 130

- and the other part thereof being disposed above the first mentioned part and supports a hammer furnished with a spring in order to drive the hammer with force against the outside of the tube, the said second part being adapted to carry out a rotary movement around the tube, whereby the hammer is withdrawn from the said tube by the said cams and its spring is compressed and the tension of the latter and thus the beating force of the hammer may be varied by the adjustable cams, and during the longitudinal movement of the first part the rotary second part also is taken along by the latter, so as to perform also a simultaneous longitudinal movement.
12. A device for packing tubes filled with sand or the like, comprising in combination, means for immovably securing the filled tube in position, and a beating device adapted to play on the tube, the said beating device consisting of two parts, one part carrying adjustable cams and being adapted to carry out a movement in the longitudinal direction of the tube and the other part thereof being disposed above the first mentioned part and supports a number of radially disposed hammers, each hammer being furnished with a spring in order to drive its hammer with force against the outside of the tube, the said second part being adapted to carry out a rotary movement around the tube, whereby the hammers are withdrawn from the said tube by the said cams and their springs are compressed and the tension of the latter and thus the beating force of the hammers may be varied by the said adjustable cams, and during the longitudinal movement of the first part the rotary second part also is taken along by the latter, so as to perform also a simultaneous longitudinal movement.
13. A device for packing tubes filled with sand or the like, comprising in combination, means for immovably securing the filled tube in position, and a beating device adapted to play on the outside of the tube, the said beating device consisting of two parts, one part carrying tensioning cams and being adapted to carry out a movement in the longitudinal direction of the tube, the said cams partly extending into the slots of a slotted adjustable member arranged on this part of the beating device and by the adjustment of the said member all cams are simultaneously and to the same extent adjusted, and the other part of the said beating device is disposed above the part first mentioned and supports a flexible hammer and further is adapted to carry out a rotary movement around the tube, whereby the flexible hammer is withdrawn from the tube and its beating force may be varied by the said adjustable cams, and during the longitudinal movement of the first part the rotary second
- part also is taken along by the latter, so as to perform also a simultaneous longitudinal movement.
14. A device for packing tubes filled with sand or the like, comprising in combination, means for immovably securing the filled tube in position, and a beating device adapted to play on the tube, the said beating device consisting of two parts, one part carrying tensioning cams and being adapted to carry out a movement in the longitudinal direction of the tube, the said cams partly extending into the slots of a slotted adjustable member arranged in this part of the beating device and by the adjustment of the said member all cams are simultaneously and to the same extent adjusted, and the other part of the beating device is disposed above the first mentioned part and supports a member of radially disposed flexible hammers and further is adapted to carry out a rotary movement around the tube, whereby the flexible hammers are withdrawn from the tube and their beating force may be varied by the said adjustable cams, and during the longitudinal movement of the first part the rotary second part also is taken along by the latter, so as to perform a simultaneous longitudinal movement.
15. A device for packing tubes filled with sand or the like, comprising in combination, means for immovably securing the filled tube in position, and a beating device adapted to play on the outside of the tube, the said beating device consisting of two parts, one part carrying tensioning cams and being adapted to carry out a movement in the longitudinal direction of the tube the said cams partly extending into the slots of a slotted adjustable member arranged in this part of the beating device and by the adjustment of the said member cams are simultaneously and to the same extent adjusted, and the other part of the said beating device is disposed above the part first mentioned and supports a hammer furnished with a spring in order to drive the hammer with force against the outside of the tube, the said second part being adapted to carry out a rotary movement around the tube, whereby the hammer is withdrawn from the said tube by the said cams and its spring is compressed and the tension of the latter and thus the beating force of the hammer may be varied by the said adjustable cams, and during the longitudinal movement of the first part the rotary second part also is taken along by the latter, so as to perform also a simultaneous longitudinal movement.
16. A device for packing tubes filled with sand or the like, comprising in combination, means for immovably securing the filled tube in position, and a beating device adapted to play on the tube, the said beating device consisting of two parts, one part car-

rying tensioning cams and being adapted to carry out a movement in the longitudinal direction of the tube, the said cams partly extending into the slots of a slotted adjustable member arranged in this part of the beating device and by the adjustment of the said member all cams are simultaneously and to the same extent adjusted; and the other part of the beating device is disposed above the part first mentioned and supports a number of radially disposed hammers, each hammer being furnished with a spring in order to drive its hammer with force against the outside of the tube, the said second part being adapted to carry out a rotary movement around the tube, whereby the hammers are withdrawn from the said tube by the said cams and their springs are compressed and the tension of the latter and thus the beating force of the hammers may be varied by the said adjustable cams, and during the longitudinal movement of the first part the rotary second part also is taken along by the latter, so as to perform also a simultaneous longitudinal movement.

17. A device for packing tubes filled with sand or the like, comprising in combination, means for immovably securing the filled tube in position, and a beating device adapted to play on the outside of the tube, the said beating device consisting of two parts, one part carrying tensioning cams and being adapted to carry out a movement in the longitudinal direction of the tube, the said cams partly extending into curved slots of a slotted adjustable annular disc arranged in this part of the beating device and by the adjustment of the said disc all cams are simultaneously and to the same extent adjusted, and the other part of the said beating device is disposed above the part first mentioned and supports a flexible hammer and further is adapted to carry out a rotary movement around the tube, whereby the flexible hammer is withdrawn from the tube and its beating force may be varied by the said adjustable cams, and during the longitudinal movement of the first part the rotary second part also is taken along by the latter so as to perform also a simultaneous longitudinal movement.

18. A device for packing tubes filled with sand or the like, comprising in combination, means for immovably securing the filled tube in position, and a beating device adapted to play on the tube, the said beating device consisting of two parts, one part carrying tensioning cams and being adapted to carry out a movement in the longitudinal direction of the tube, the said cams partly extending into curved slots of a slotted adjustable annular disc arranged in this part of the beating device and by the adjustment of the said disc all cams are simultaneously and to the same extent adjusted, and the

other part of the beating device is disposed above the part first mentioned and supports a number of radially disposed flexible hammers and further is adapted to carry out a rotary movement around the tube, whereby the flexible hammers are withdrawn from the tube and their beating force may be varied by the said adjustable cams, and during the longitudinal movement of the first part the rotary second part also is taken along by the latter, so as to perform a simultaneous longitudinal movement.

19. A device for packing tubes filled with sand or the like, comprising in combination, means for immovably securing the filled tube in position, and a beating device adapted to play on the tube, the said beating device consisting of two parts, one part carrying tensioning cams and being adapted to carry out a movement in the longitudinal direction of the tube, the said cams partly extending into curved slots of a slotted adjustable annular disc arranged in this part of the beating device and by the adjustment of the said disc all cams are simultaneously and to the same extent adjusted, and the other part of the said beating device is disposed above the part first mentioned and supports a hammer furnished with a spring in order to drive the hammer with force against the outside of the tube, the said second part being adapted to carry out a rotary movement around the tube, whereby the hammer is withdrawn from the said tube by the said cams and its spring is compressed and the tension of the latter and thus the beating force of the hammer may be varied by the said adjustable cams, and during the longitudinal movement of the first part the rotary second part also is taken along by the latter, so as to perform also a simultaneous longitudinal movement.

20. A device for packing tubes filled with sand or the like, comprising in combination, means for immovably securing the filled tube in position, and a beating device adapted to play on the outside of the tube, the said beating device consisting of two parts, one part carrying tensioning cams and being adapted to carry out a movement in the longitudinal direction of the tube, the said cams partly extending into curved slots of a slotted adjustable annular disc arranged in this part of the beating device and by the adjustment of the said disc all cams are simultaneously and to the same extent adjusted, and the other part of the said beating device is disposed above the part first mentioned and supports a number of radially disposed hammers, each hammer being furnished with a spring in order to drive its hammer with force against the outside of the tube, the said second part being adapted to carry out a rotary movement around the tube, whereby the hammers are withdrawn from

the said tube by the said cams and their springs are compressed and the tension of the latter and thus the beating force of the hammers may be varied by the said adjustable cams, and during the longitudinal movement of the first part the rotary second part also is taken along by the latter, so as to perform also a simultaneous longitudinal movement.

10 21. A device for packing tubes filled with sand or the like, comprising in combination, means for immovably securing the filled tube in position, a beating device adapted to play on the outside of the tube, the said beating device consisting of two parts, one part carrying adjustable tensioning cams and being adapted to carry out a movement in the longitudinal direction of the tube, and the other part thereof being disposed above the 15 part first mentioned and supports a flexible hammer and further is adapted to carry out a rotary movement around the tube, and a lever pivotally secured to the said rotary second part, the free end of the said lever 20 being attached to the said hammer and during the rotation the flexible hammer is withdrawn from the tube by the contact of the free end of the lever with the cams and the beating force of the hammer may be varied 25 by means of adjusting the said cams, and during the longitudinal movement of the first part the rotary second part also is taken along by the latter, so as to perform also a simultaneous longitudinal movement. 30

35 22. A device for packing tubes filled with
sand or the like, comprising in combination,
means for immovably securing the filled tube
in position, a beating device adapted to play
on the outside of the tube, the said beating
40 device consisting of two parts, one part
carrying adjustable tensioning cams and be-
ing adapted to carry out a movement in the
longitudinal direction of the tube, and the
45 other part thereof being disposed above the
part first mentioned and supports a number
of radially disposed flexible hammers and
further is adapted to carry out a rotary
movement around the tube, and levers piv-
otally secured to the said rotary second part,
50 one lever being provided for each hammer
and the free end of each lever is attached to
its hammer and during the rotation the
flexible hammers are withdrawn from the
tube by the contact of the free end of its
55 hammer with the cams and the beating force
of the hammers may be varied by means of
adjusting the said cams, and during the lon-
gitudinal movement of the first part the ro-
tary second part also is taken along by the
60 latter, so as to perform also a simultaneous
longitudinal movement.

23. A device for packing tubes filled with sand or the like, comprising in combination, means for immovably securing the filled tube 65 in position, a beating device adapted to play

on the outside of the tube, the said beating device consisting of two parts, one part carrying adjustable tensioning cams and being adapted to carry out a movement in the longitudinal direction of the tube, and the other part thereof being disposed above the part first mentioned and supports a hammer furnished with a spring in order to drive the hammer with force against the outside of the tube, the said second part being adapted to carry out a rotary movement around the tube, and a lever pivotally secured to the said rotary second part, the free end of the said lever being attached to the said hammer and during the rotation the hammer is withdrawn from the tube by the contact of the free end of the lever with the cams and its spring is compressed and the tension of the latter and thus the beating force of the hammer may be varied by means of adjusting the said cams, and during the longitudinal movement of the first part the rotary second part also is taken along by the latter, so as to perform also a simultaneous longitudinal movement.

24. A device for packing tubes filled with sand or the like, comprising in combination, means for immovably securing the filled tube in position, a beating device adapted to play on the outside of the tube, the said beating device consisting of two parts, one part carrying adjustable cams and being adapted to carry out a movement in the longitudinal direction of the tube, and the other part thereof being disposed above the part first mentioned and supports a number of radially disposed hammers, each hammer being furnished with a spring in order to drive its hammer with force against the outside of the tube, the said second part being adapted to carry out a rotary movement around the tube, and levers pivotally secured to the said rotary second part, one lever being provided for each hammer and the free end of each lever is attached to its hammer and during the rotation the hammers are withdrawn from the said tube and their springs are compressed and the tension of the latter and thus the beating force of the hammers may be varied by the said adjustable cams, and during the longitudinal movement of the first part the rotary second part also is taken along by the latter, so as to perform also a simultaneous longitudinal movement.

25. A device for packing tubes filled with sand or the like, comprising in combination, means for immovably securing the filled tube in position, and a beating device adapted to play on the outside of the tube, the said beating device consisting of two parts, one part carrying adjustable tensioning cams and being adapted to carry out a movement in the longitudinal direction of the tube and the other part thereof being disposed above the part first mentioned and

- supports a flexible screw-threaded hammer 60
screwed into a sleeve, which is located in
the second part, in order to adapt the length
of the hammer to the diameter of the tube
5 to be operated on by means of screwing the
said hammer more or less far into the said
sleeve, the said second part being adapted
to carry out a rotary movement around the
tube, whereby the flexible hammer is with- 65
10 drawn from the tube by the said cams and
its beating force may be varied by the said
adjustable cams, and during the longitudi-
nal movement of the first part the rotary
second part also is taken along by the latter,
15 so as to perform also a simultaneous longi-
tudinal movement.
26. A device for packing tubes filled with
sand or the like, comprising in combination,
20 means for immovably securing the filled
tube in position, and a beating device adapt-
ed to play on the outside of the tube, the
said beating device consisting of two parts,
25 one part carrying adjustable cams and being
adapted to carry out a movement in the
longitudinal direction of the tube and the
other part thereof being disposed above the
part first mentioned and supports a number
30 of radially disposed flexible screw-threaded
hammers, each hammer being screwed into
a sleeve located in the second part, in order
to adapt the length of the hammer to the
diameter of the tube to be operated on by
35 means of screwing the said hammer more or
less far into the said sleeve, the second part
being adapted to carry out a rotary move-
ment around the tube, whereby the flexible
hammers are withdrawn from the tube by
40 the said cams and their beating force may
be varied by the said adjustable cams, and
during the longitudinal movement of the
first part the rotary second part also is taken
along by the latter, so as to perform also a
45 simultaneous longitudinal movement.
27. A device for packing tubes filled with
sand or the like, comprising in combination,
50 means for immovably securing the filled tube
in position, and a beating device adapted
to play on the outside of the tube, the said
beating device consisting of two parts, one
55 part carrying adjustable cams and being
adapted to carry out a movement in the lon-
gitudinal direction of the tube and the
other part thereof being disposed above the
part first mentioned and supports a screw-
60 threaded hammer, which is furnished with
a spring in order to drive the hammer with
force against the outside of the tube and
which is screwed into a sleeve located in the
second part in order to adapt the length of
65 the hammer to the diameter of the tube to
be operated on by means of screwing the
said hammer more or less far into the said
sleeve, the said second part being adapted to
carry out a rotary movement around the tube,
70 whereby the hammer is withdrawn from the
said tube by the said cams and its spring is
compressed and the tension of the latter and
thus the beating force of the hammer may
be varied by the said adjustable cams, and
75 during the longitudinal movement of the
first part the rotary second part also is
taken along by the latter, so as to perform
also a simultaneous longitudinal movement.
28. A device for packing tubes filled with
sand or the like, comprising in combination,
80 means for immovably securing the filled
tube in position, and a beating device adapt-
ed to play on the outside of the tube, the
said beating device consisting of two parts,
85 one part carrying adjustable tensioning
cams and being adapted to carry out a
movement in the longitudinal direction of
the tube and the other part thereof being
disposed above the part first mentioned and
90 supports a number of radially disposed
screw-threaded hammers, each hammer
being furnished with a spring in order to
drive the hammer with force against the
outside of the tube and being screwed into a
95 sleeve located in the second part in order
to adapt the length of the hammer to the
diameter of the tube to be operated on by
means of screwing the said hammer more or
less far into the said sleeve, the second part
100 being adapted to carry out a rotary move-
ment around the tube, whereby the hammers
are withdrawn from the said cams and their
springs are compressed and the tension of
the latter and thus the beating force of the
105 hammers may be varied by the said adjust-
able cams, and during the longitudinal
movement of the first part the rotary second
part also is taken along by the latter, so as
to perform also a simultaneous longitudinal
movement.
29. A device for rapping tubes which have
been filled with sand comprising rapping
hammers arranged for longitudinal move-
ment and also for revoluble movement about
the work, said hammers being also arranged
110 for axial adjustment in accordance with the
diameter of the work.

In testimony whereof I affix my signature
in presence of two witnesses.

JOHANN HOFFMANN.

Witnesses:

ALFRED HAMBURGER,
JOSEF GURMANN.
